COLLAPSIBLE GARMENT HANGER

Filed Sept. 11, 1947

UNITED STATES PATENT OFFICE

2,488,219

COLLAPSIBLE GARMENT HANGER

Kurt R. Miller, Flagstaff, Ariz.

Application September 11, 1947, Serial No. 773,437

2 Claims. (Cl. 223—89)

1

This invention relates to new and useful improvements and structural refinements in collapsible garment hangers, and the principal object of the invention is to provide a device of the character herein described, which, in its extended position, may be conveniently and effectively employed for supporting coats, dresses or the like, and which, when collapsed, may be easily and conveniently carried in the pocket or handbag of the user.

A further object of the invention is to provide a collapsible garment hanger which is simple in construction, pleasing in appearance, and which may be quickly and easily extended or collapsed.

An additional object of the invention is to provide a collapsible garment hanger which will readily lend itself to economical manufacture and which is otherwise well adapted for the purpose for which it is intended.

With the above more important objects in view, and such other objects as may become apparent as this specification proceeds, the invention consists essentially of the arrangement and construction of parts as illustrated in the accompanying drawings, in which:

Figure 1 is a side elevational view of the invention in its extended position.

Figure 2 is a longitudinal edge view of the device shown in Figure 1.

Figure 3 is an elevational view of the hanger in its collapsed position, and

Figure 4 is an elevational view of the collapsed hanger positioned in the pocket of the user.

Like characters of reference are employed to designate like parts in the specification and throughout the several views.

Referring now to the accompanying drawings in detail, the invention consists of a collapsible garment hanger designated generally by the reference character 10, the same embodying in its construction an end member 11 including a pair of flattened, tapered tubular sleeves 12 disposed in spaced parallel relation, the major end portions of these sleeves being rigidly secured together by means of a connecting plate 13.

A pair of flattened, tapered tubular extensions 14 are slidably telescoped in the sleeves 12, that is to say, the major end portion of each extension is slidably telescoped in the minor end portion of each sleeve, as is best shown in Figure 1, whereby the extensions will be slidably connected to the sleeves, yet separation thereof from the sleeves will be prevented by virtue of the tapered configuration, as will be clearly apparent.

A U-shaped extension piece 15, including an

end portion 16 and a pair of spaced parallel side portions 17 has the side portions thereof slidably telescoped in the extensions 14, the side portions 17 being, of course, also tapered, as has been already explained in connection with the members 12 and 14.

A hook 18 includes a bill portion 19 and a clamp portion 20, the latter simply assuming the form of a doubled end portion of the strap from which the hook is formed.

When the invention is placed in use, the sections 14 and 15 are extended from the sleeves 12 and the hook 18 is applied to one of the extensions 14, after which a dress, trousers or coat may be applied to the hanger in the conventional, well-known manner.

However, when the hanger is not in use, it may be retracted or collapsed by simply pushing the sections 14 and 15 into the sleeves 12, as best shown in Figure 3. Needless to say, preparatory to this action, the hook 18 should be removed from the extensions 14, but it may thereafter be applied, more particularly, the clamp portion 20 of the hook may be applied to the slot or recess 21 in the plate 13, in which manner the entire hook will function as an effective "spring clip" for retaining the collapsed hanger in the pocket 22 of a coat 23, or the like.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention what is claimed as new is:

1. A collapsible garment hanger, comprising in combination, an end member including a pair of flattened and tapered tubular sleeves disposed in spaced parallel relation, a connecting plate securing said sleeves together, a pair of flattened and tapered tubular extensions each slidably telescoped in one of said sleeves, a U-shaped extension piece having flattened and tapered side portions, said side portions being slidably telescoped in said extensions, and a hook selectively attachable to one of said sections and to said plate.

2. In a collapsible garment hanger, the combination of a supporting plate, a pair of substan-

tially tubular sleeves secured to said plate and extending therefrom in spaced parallel relation, a pair of substantially tubular extensions each slidably telescoped in one of said sleeves, a U-shaped extension piece having side portions thereof slidably telescoped in said extensions, said plate being provided between said sleeves with an opening, and a suspension member including a hook-shaped clamp portion, the clamp portion of said hook being engageable selectively with one of said sections and with the opening in said plate. 10
